I claim the ornamental design for an ostomy appliance seal, as shown and described.

DESCRIPTION

FIG. 1 is a front perspective view of an ostomy appliance seal showing my new design;

FIG. 2 is a front view thereof;

FIG. 3 is a right side view thereof;

FIG. 4 is a top view thereof;

FIG. 5 is a rear view thereof;

FIG. 6 is a bottom view thereof; and,

FIG. 7 is a left side view thereof.

The ornamental design which is claimed is shown in solid lines in the drawings.
